TABLE TENNIS BAT

George H. Perryman, Clifton, N. J.

Application July 7, 1939, Serial No. 283,162

3 Claims. (Cl. 273—76)

This invention relates to a new and useful improvement in racquets or paddles for use in the playing of the game "Ping-pong", "table tennis" and the like, the invention relating more particularly to an improved racquet having a minimum weight together with maximum strength and rigidity.

One of the principal objects of the invention is the provision of a novel bat or racquet of this character constructed primarily of light material such as laminated wood, the racquet being provided with reinforcing means extending beyond the outer periphery of the body portion whereby such racquet may be put to considerable hard service without breaking, splitting or otherwise becoming defective.

A further object of the invention is to provide an improved racquet structure for table tennis and like games having an improved measure of stiffness, resiliency and flexibility, and at the same time being of light weight.

A further object of the invention is the provision of an improved device of the character described which is provided with a reinforcing member extending around substantially the entire periphery of the playing portion of the racquet, the playing portion having an annular recess to receive the member, such reinforcing member being firmly secured at its ends to the side edges of such playing portion, the reinforcing strip being so formed as to add considerably to the strength of the device and at the same time prevent injury to the paddle in the event that it strikes the table or other hard object with a forcible blow.

In the drawing, Fig. 1 is a front elevation of the preferred embodiment of the present invention, with portions of the device being shown in section; Fig. 2 is a side elevation thereof; Fig. 3 is a broken transverse section taken on the line 3—3 of Fig. 1; and Figs. 4 and 5 are sectional views similar to Fig. 3, such views showing modifications in the construction of the device constituting the present invention.

Referring now more particularly to the drawing, the body portion of the paddle indicated at 10 is generally circular in shape and is provided with a narrow, radially disposed extension 11 which serves as a base for the handle structure. This body portion is preferably made from laminated wood or other suitable light weight sheet material. By constructing this portion from laminated wood, the possibility of warping is reduced and the paddle will, of course, possess

greater strength than if merely a single thickness of wood or other material were employed.

The body portion is further formed with curved web portions 12 between the handle portion and said body portion which give the handle an increased measure of strength and rigidity. The handle structure further includes facings 14 on opposite sides thereof, each of said facings having one flat surface which is secured to the portion 12 and the opposed surface is curved, thus forming a handle structure which is substantially circular in transverse section. The upper ends of such facings 14 are formed with concave, cutout portions 15, which portions are engaged by the thumb and forefinger of the player. The opposed playing surfaces of the body portion 10 may be flat as shown in Figs. 1 and 2 or they may, if desired, be provided with resilient facings 17 made preferably of rubber and having a plurality of circular, spaced protuberances 18, all as well known in the art.

Around the periphery 20 of the body portion is formed an annular recess 21 which is substantially semicircular in transverse section. This recess terminates at each end thereof adjacent to the curved web portions 12, as shown in Fig. 1. A metallic strip 23 which is preferably circular in transverse section extends around the periphery of this body portion and the inner surface thereof is positioned within the recess 21 as shown in Fig. 3. Adjacent each terminal of this member, an aperture 24 is formed and a pin, screw, or other similar article passes through such aperture and into the body portion 10, thus mounting the strip firmly upon the body portion. It will thus be apparent from this construction that substantially the entire periphery of the body portion of the racquet is effectively protected by this strip 23, which, as shown in Fig. 3, extends beyond the periphery of the body portion, and accordingly, during the course of play, when the bat strikes the playing table or other member, the protective band effectively secures the marginal edges of the body portion against injury.

In the modification shown in Fig. 4, the recess 26 around the periphery of the body portion 10 is angular in transverse section and the binding strip 27 is similarly shaped around the inner edge thereof and the exposed surface is curved in transverse section.

In Fig. 5, the recess 29 is substantially rectangular in transverse section and inside portion of the binding strip 30 is similarly shaped.

The three foregoing embodiments of the present invention are illustrative only and various

changes may be made therein without departing from the spirit of the invention. For instance, the reinforcing strip could be made from a material other than metal, such as a plastic. Also, 5 means other than those shown may be employed for securing such strip to the body portion.

What I claim is:

1. A table tennis bat having a body portion composed of several laminated plies including 10 outer plies located at the opposite faces of the bat, at least one inner ply located between the outer plies and having its periphery disposed inwardly of the peripheries of the outer plies to form a groove between the outer plies, and a reinforcing member seated within said groove and having its inner edge disposed inwardly of the peripheries of the outer plies and concealed by the outer plies and its outer edge extending beyond the edge of the outer plies to thereby protect the same. 20

2. A table tennis bat having a body portion

composed of a plurality of laminations, said body portion having a groove formed in its peripheral edge between several of the laminations, and a reinforcing strip seated in the groove and having its outer edge extending beyond the edges of 5 the laminations between which it is located to thereby protect the outer edges of said laminations.

3. A table tennis bat having a body portion composed of several laminated plies including 10 outer plies located at the opposite faces of the bat and between which a groove is provided, a reinforcing member seated within said groove and extending around the edge of the body portion, the marginal edge portions of said outer 15 plies extending over and outwardly of the inner edge of said member and concealing the same, the member having a smooth, rounded outer edge extending beyond the outer plies to thereby protect the same. 20
